CLAIM

The ornamental design for a shading system, as shown and described.

DESCRIPTION

FIG. 1 is a front perspective view of a first embodiment of a shading system in an upright position and showing the new design;

FIG. 2 is a front view of the shading system of FIG. 1;

FIG. 3 is a rear view of the shading system of FIG. 1; FIG. 4 is a left side view of the shading system of FIG. 1; FIG. 5 is a right side view of the shading system of FIG. 1; FIG. 6 is a top plan view of the shading system of FIG. 1; FIG. 7 is a bottom plan view of the shading system of FIG. 1;

FIG. 8 is a front perspective view of a second embodiment of a shading system in an upright position and showing the new design;

FIG. 9 is a front view of the shading system of FIG. 8; FIG. 10 is a rear view of the shading system of FIG. 8; FIG. 11 is a left side view of the shading system of FIG. 8; FIG. 12 is a right side view of the shading system of FIG. 8;

FIG. 13 is a top plan view of the shading system of FIG. 8; FIG. 14 is a bottom plan view of the shading system of FIG. 8;

FIG. 15 is a front perspective view of a third embodiment of a shading system in an upright position and showing the new design;

FIG. 16 is a front view of the shading system of FIG. 15; FIG. 17 is a rear view of the shading system of FIG. 15; FIG. 18 is a left side view of the shading system of FIG. 15; FIG. 19 is a right side view of the shading system of FIG. 15;

FIG. 20 is a top plan view of the shading system of FIG. 15; FIG. 21 is a bottom plan view of the shading system of FIG. 15;

FIG. 22 is a front perspective view of a fourth embodiment of a shading system in an upright position and showing the new design;

FIG. 23 is a front view of the shading system of FIG. 22; FIG. 24 is a rear view of the shading system of FIG. 22; FIG. 25 is a left side view of the shading system of FIG. 22; FIG. 26 is a right side view of the shading system of FIG. 22;

FIG. 27 is a top plan view of the shading system of FIG. 22; and,

FIG. 28 is a bottom plan view of the shading system of FIG. 22.

The dashed lines shown herein depict environmental subject matter or a portion of the shading system that forms no part of the claimed design. The dot-dashed lines shown herein define the bounds of the claimed design and form no part thereof. Shade lines represent the approximate three-dimensional contours of the fabric shade and are not intended to indicate surface ornamentation or decoration.
